HENRY A. NICHOLSON, OF ARKLES BAY, AUCKLAND, NEW ZEALAND, ASSIGNOR TO
ERNEST A. CRAIG, OF AUCKLAND, NEW ZEALAND.

STEAM GENERATOR.

Application filed June 24, 1919. Serial No. 306,400.

This invention relates to steam-generators, especially those of the type disclosed in my pending application, Serial No. 284,657, filed March 24, 1919, in which water is forced to flow in a single direction through a system of piping which is subjected to the heat of a furnace, whereby the fluid is gradually heated and given a high pressure as it advances to the delivery end of the generator, where it is permitted to expand in a steam-drum.

One of the main objects of the invention is to provide an inexpensive and efficient generator of a simple type, and to this end the water is pumped directly through a reserve-drum to a system of tubing comprising numerous coils, arranged preferably one above another in the flame or heating chamber of the generator; the fluid descending coil by coil from the top to the bottom of the system, and being then led to a steam-drum. Both the steam-drum and reserve-water-drum are placed in the upper part of the generator; and the water in the water-drum is hence heated moderately before it flows into the coils of tubing, while the steam-drum is heated for supplying additional heat to any residuum of fluid therein in the form of water at the temperature and pressure of the steam in the drum.

Means is provided for drawing upon the reserve water in the water-drum in case the feed-pump is temporarily stopped, or in case any obstacle be present in the system; the water-drum and steam-drum being directly connectible, and other provision being made for causing the heated fluid to circulate upwardly in the coil system to the drums, and thence down to the bottom of the coil system, so that generation of steam may be maintained temporarily while the pump is shut down.

The tubes in the coils, which together may form a single line of piping, are preferably of the same diameter as the water-main which supplies the generator, and they may be jacketed by a refractory heat-conducting and radiating material of the kind set forth in said application; means being provided for separating each jacket a trifle from its enclosed tube, to avoid undue cooling of the jacket by the fluid in the tube; it being intended that the jackets should maintain an incandescent condition, so as to lengthen

or prolong the life of the flames which lap the jackets.

If it is desired to secure a more rapid circulation of the water in the generator when the pump is closed down, there may be used an auxiliary circulator or pump which may be driven by any suitable source of power to set the water actively circulating throughout the generator, thus avoiding liability of injury to the generator by reason of the stagnation of the fluid at any point therein.

Other features and advantages will hereinafter appear.

In the accompanying drawings,

Figure 1 is a sectional side elevation of one form of generator embodying the present improvements.

Figure 2 is a diagram to illustrate the flow of the water through the generator.

Figure 3 is a sectional side elevation, illustrating the connection of the horizontal coils with one another.

Figure 4 is an enlarged sectional diagram of adjoining tubes with their refractory jackets, and illustrating a supporting block of similar material placed between the tube jackets.

Figure 5 is a plan of the generator.

Figure 6 is a sectional plan of one of the horizontal coils mounted in the flame-chamber.

Figure 7 is a diagrammatic longitudinal section of one of the water-tubes, showing the refractory jacket thereon, and the means for separating the jacket a trifle from the tube.

By means of one or more force-pumps 10, water is supplied under great pressure through a main 11 to a reserve water-drum 12, a back-check-valve 13 being preferably provided between the pump and the drum. The water-drum is heated by means of the hot gases flowing up through the generator to a stack 14; the top of the generator comprising a dome 15 within which said drum is arranged in such a manner that the escaping gases circulate freely around the same.

In the upper part of said drum 12, at the other end from the inlet 16, is an outlet 17 connected by an elbow 18 and a short vertical pipe 19 to another elbow 20 and a horizontal pipe 21 to the receiving end 22

of a system of recumbent coils 23 arranged within a combustion-chamber 24, the latter comprising front and rear walls 25, 26, and side walls 27, 28.

- 5 The coils 23 are so arranged in tiers or one above another that the water flows entirely through all the tubes 29 in one coil or tier, and then down through a duct 30 to the receiving end of the next coil or tier, 10 and then through all the tubes 29 in the second tier to the delivery end thereof, and thence down through a duct or union 30 to the receiving end of the third tier, and so on to the bottom of the system of tubing coils. 15 At Figure 1, the tubes 29 in this system or gridwork, which may be of the same diameter as the water-mains, are seen in cross-section, while Figure 6 is a sectional plan, showing a single tier or coil of the tubes, 20 which are joined at alternate ends by U-passages 31 formed in headers 32, making a zigzag coil. The gridwork may be considered as comprising a series of horizontal coils arranged one under another, and each 25 connected to the next below it, to form a single main through which the fluid is forced to advance always in one direction by means of the force-pumps, from top to bottom of the flame-chamber; and each coil may comprise a row of tubes connected at their ends 30 in zigzag arrangement. The headers may have clean-out openings closed by screw-plugs 33.

This flame-chamber surmounts a fire-box 34, containing grates 35, and an ash-pit 36. The usual fire-door is seen at 37 and ash-door at 38.

It will be seen that the fluid receives its final heating in passing through the lower-most coil 23 which is immediately over the fire-box, and hence at the moment of delivery from the system the fluid is subjected to the greatest heat; at this time its heat and pressure are very high, say 350 pounds 45 or more to the square inch.

From the delivery end 39 of the lower-most coil, the fluid rises in a pipe 40 to the top of the generator, and by means of an elbow 41 is led into the lower portion of a 50 steam-drum 42, the inlet to the drum being preferably in the form of a long horizontal pipe 43 extending nearly to the opposite end of the drum (Figure 3), and having in its top small perforations 44 through which the 55 overheated fluid flows in the form of steam to fill the drum; said perforations serving to choke back the highly-heated pent-up fluid which is being forced to advance by the pumps, and preferably being of such small 60 dimensions that the pressure of the steam in the drum may be less than the pressure of fluid rising to the drum in the pipe 40. It will be seen that provision is made for converting pent-up, high-pressure, highly- 65 heated fluid into steam, consisting of a series

or multiplicity of small outlets 44, each of which, because of its fineness, causes the fluid to be retained in the converter pipe 43 at higher pressure than the steam in the 70 service drum 42, so that fluid may escape from the orifices in the form of steam. Advantage is taken of the fact that each orifice may be made small enough to perform this function, and co-operation may be secured of a multiplicity of orifices. This feature is not, however, limited to a converter pipe arranged within the steam-drum, as the converter orifices may be otherwise provided. Thus highly-heated fluid may remain pent 75 up at high pressure in the fluid-piping system and may be issued as steam without the use of a movable valve. The steam-drum 42 is a service drum, from which steam is rapidly withdrawn, whereby the tendency is to lower the pressure in the drum relatively to the pressure in the piping that supplies the drum; and the minuteness of the perforations in the converter pipe enables the pipe to hold back the fluid at a pressure above that of the steam in said drum; certain of the water content of the fluid being expanded or converted into steam as it passes from the high-pressure pipe 43 into the lower pressure drum 42. It is not essential that 80 all of the fluid enter the steam-drum in the form of steam. Such as enters in the form of water is subject to subsequent heating from the heat of the hot gases rising from the flame-chamber and circulating around the steam-drum, whereby the water in the 85 drum, having the heat and pressure of the steam, may be converted into the form of steam as the pressure decreases due to the escape of the steam from the service-pipe.

The drum is supplied with a delivery or service-pipe 45, rising from the top thereof and provided with a stop-valve 46. In case it becomes necessary to stop the operation of the pumps, or if, for any reason, the flow of fluid to the steam-drum should be obstructed or stopped, a valve 47 may be opened in a by-pass 48 between the drums, so that a circulation of fluid may be maintained in the tube system 23 independently 100 of the pumps 10.

When the valve 47 is open, the direction of the fluid flow will be reversed, that is, the fluid will flow up in the gridwork and be delivered through the pipes 21, 19 to the water-drum 12, which may communicate through the by-pass 48 to the steam-drum, from whence the cooler portion of the fluid may descend through the diagonal pipe 40 to the bottom coil in the system. Thus the generator is converted into a circulatory system, in which circulation will be maintained temporarily until the obstacle is removed and the pumps started into action again. It will also be understood that this reverse circulation of fluid may be relied upon when 115 120 125 130

warming up the generator to the point of steam production, and that thereupon the valve 47 in the by-pass 48 may be closed, and the pumps started into action, to cause steam to be delivered to the steam-drum 42, as already explained.

Another method of securing a temporary circulation of the water through the system independently of the force-pumps is also illustrated, and may be used when the valve 47 in said by-pass is open. According to this method, a centrifugal or rotary pump 49 may be operated by a motor or pulley 50, and may draw fluid up through the diagonal pipe 40 from the bottom coil 23 in the system (valve 50^a being closed in top of pipe 40), and may force the water through a vertical pipe 51 into the upper portion of the water-drum 12. From this drum steam may pass over through an upper by-pass 52 (containing a valve 53 which may now be open), into the top of the steam-drum 42. Valve 50^a at top of pipe 40 may be closed, to cut it off from the steam-drum 42. The cooler water may flow down through pipe 19 into the uppermost of the grid-sections or coils, and thence down the grid to the bottom thereof, and from thence it may be drawn up by the pump through the diagonal pipe 40 to the water-drum 12, thus keeping up the circulation, steam passing over through the open by-pass 52 to the steam-drum 42. This pump is serviceable to warm up the water quickly.

The tubes forming the coils or sections are joined at alternate ends by the U-shaped connections 31 formed in the horizontal headers 32, which are arranged one above another at the sides or ends of the flame-chamber. In Figure 3 are also shown clean-out openings closed by the plugs 33.

At Figure 1, the tubes are all shown as encased in jackets 56 of refractory heat-conducting material of the kind disclosed in my said pending application, Serial No. 284-657, filed March 24, 1919. As set forth in said application, these jackets become incandescent and prolong the life of the flame, which would otherwise be prematurely cooled, thus shortening combustion, so that an excessive proportion of combustible gases would escape from the generator. These jackets may be cylindrical, and are preferably oversize, and may be provided with internal ribs or studs 57 placed at suitable intervals, so as to keep the jackets slightly separated from the tubes, for the purpose set forth in said application, whereby the heating of the tubes by the jackets is effective through radiation, and whereby the pipes may have little or no tendency to cool the jackets, which it is desired to maintain in an incandescent condition.

At Figure 4 is shown a method of supporting the jackets by means of blocks 58

of refractory material, having concave sides and fitting between adjacent jackets 56. These blocks or supports may be placed either between laterally adjacent tubes or between tubes arranged one above another, or both methods may be used.

The opening 59 in the top or bridge above the fire-box for the escape of the flames is seen at Figure 3. Among the tube coils may be placed baffle-plates 60 extending alternately from the back and front of the flame-chamber, so that the flames must pursue a zigzag course in rising to the top of the generator. It will be seen that the tubes are placed rather closely together side by side, so that the flames cannot readily course upwardly, while the tube coils are separated considerably one above another, to give ample room for the flames, so that combustion may proceed slowly, and so that the life of the flames may be prolonged, and the tubes in the upper part of the combustion-chamber may be caused to do a proper share of the heating of the fluid, so that an undue proportion of the work of heating the water will not fall upon the tubes closest to the fire-box.

Variations may be resorted to within the scope of the invention, and portions of the improvements may be used without others.

Having thus described my invention, I claim:

1. In a steam generator, the combination of a system of tubing and a drum connected therewith, a pump for forcing fluid only once at high pressure through the system in a single direction, means for heating the fluid to high temperature as it advances, a low pressure service steam drum, and a converter connected to the delivery end of the system of tubing and having a portion extending within the steam drum, said converter having within said drum means for converting the high pressure fluid into low pressure steam comprising numerous small perforations opening into the drum, said perforations of such small dimension that the pressure of the fluid in the converter is maintained at a substantially higher point than the pressure of steam in the service drum, and upper and lower pipes for connecting the drums, said pipes having valves therein which when open permit circulation of the fluid through the drums and tubing.

2. In a steam generator, the combination of a system of tubing, a water drum communicating with the inlet end of said tubing, a pump communicating with said water drum for forcing fluid only once at high pressure through the system in a single direction, means for heating and maintaining the fluid at high temperature as it advances, a low pressure service steam drum connected to the outlet end of said tubing and means for

- converting the highly heated pent up fluid into low pressure steam, comprising a converter from which open numerous relatively small outlets which choke back the pent up fluid and through which fluid escapes into low pressure steam whereby the pressure of fluid in the fluid tubes is kept at a higher point than the pressure of steam in the service steam drum, and means between 5 the steam drum and water drum to permit circulation of the fluid around and around through the system.
3. A steam-generator comprising a combustion or flame-chamber filled with a system of coils of tubing, said coils arranged one above another and connected in series to form a single fluid-course, hydraulic means for forcing fluid to advance in one direction from one end to the other of the system, a reserve-water-drum included between said forcing means and said system of coils, a steam-drum to which the delivery end of said system of coils is connected, a by-pass being provided between said drums, and a 10 valve normally closing said by-pass, but when opened permitting circulation of fluid in the opposite direction through the tube system and drums, a heating chamber being provided in which said steam-drum is mounted.
4. A steam-generator comprising a system of continuous tubing, a feed-pump for forcing fluid to advance in a single direction through the tubing, means for heating the fluid to high pressure and temperature as the fluid advances through the system, a steam-drum at the delivery end of the tubing system, means for temporarily converting the generator into a circulatory system, and an auxiliary pump connected to the system to cause the fluid to circulate therein at the cessation of the operation of the feed-pump, a heating chamber being provided in which said steam-drum is mounted.
5. A steam-generator comprising a system of continuous tubing, a feed-pump for forcing fluid to advance in a single direction through the tubing, means for heating the fluid to high pressure and temperature as the fluid advances through the system, a steam-drum at the delivery end of the tubing system, means for temporarily converting the generator into a circulatory system, an auxiliary pump, and means for operating said auxiliary pump, said auxiliary pump connected to draw fluid from one part of said tubular system, to deliver it to another part thereof, whereby circulation may be maintained while the feed-pump is ineffective, or while the generator is being warmed up, and means 15 to connect and disconnect parts of the generating system from one another, so that repeated circulation of fluid may be secured by said auxiliary pump at will, a heating chamber being provided in which said steam-drum is mounted.
6. A steam-generator comprising a system of continuous tubing, a feed-pump for forcing fluid to advance in a single direction through the tubing, means for heating the fluid to high pressure and temperature as the fluid advances through the system, a steam-drum at the delivery end of the tubing system, means for temporarily converting the generator into a circulatory system, an auxiliary pump, said auxiliary pump connected to draw fluid from one part of said tubular system, to deliver it to another part thereof, whereby circulation may be maintained while the feed-pump is ineffective, or while the generator is being warmed up, and means to connect and disconnect parts of the generating system from one another, so that repeated circulation of fluid may be secured by said auxiliary pump at will, a heating chamber being provided in which said steam-drum is mounted.
7. A steam-generator comprising a system of tubing, a feed-pump for forcing fluid to advance in a single direction through the tubing, means for heating the fluid to high pressure and temperature as the fluid advances through the system, a steam-drum at the delivery end of the tubing system, a reserve water-drum for said system of tubing, an auxiliary pump, means for operating said auxiliary pump, said auxiliary pump connected to draw fluid from one part of said tubular system, to deliver it to another part thereof, whereby circulation may be maintained while the feed-pump is ineffective, or while the generator is being warmed up, a by-pass connecting said steam-drum and said reserve water-drum, and a valve to close said by-pass, a heating chamber being provided in which said steam-drum is mounted.
8. A steam generator comprising a combustion or flame chamber, steam and water drums in the upper portion of the chamber, coils connected in series and extending from the water drum downwardly in the chamber thence through a pipe upwardly to the steam drum, means for forcing fluid through the water drum and the coils into the steam drum in a single direction of flow, and a plurality of pipes having valves therein for connecting the upper and lower portions of said drums, said pipes serving to allow circulation in the system when the valves are open.

HENRY A. NICHOLSON.
